UNDERGROUND STORMWATER STORAGE SYSTEM

CROSS-REFERENCE TO RELATED APPLICATIONS

This application claims priority to U.S. Provisional Patent Application No. 62/714,475 filed Aug. 3, 2018, U.S. Provisional Patent Application No. 62/852,562 filed May 24, 2019, and U.S. application Ser. No. 16/516,072 filed Jul. 18, 2019, the entire disclosures of which are incorporated herein by reference. This application is a continuation-in-part of U.S. application Ser. No. 16/516,072.

BACKGROUND

Embodiments relate generally to an underground stormwater storage system. More particularly, embodiments relate to a system in which stormwater may be captured and removed from an underground stormwater storage system through pipes and/or through outlets in the top-most regions of the system.

Current underground stormwater storage systems may be designed to capture and dispose of stormwater into an underground area. Surrounded by porous backfill, underground stormwater storage systems may often utilize void space within the porous backfill for added storage. The underground stormwater storage system may expel stormwater contaminated with sand and/or silt into porous backfill with each storm event. The expulsion of contaminated stormwater may deposit sand and/or silt and saturate the void space within the porous backfill, preventing attainment of full design storage volume. Overloading an underground stormwater storage system with clogged void space may prevent the underground stormwater storage system from operating properly, which may lead to stormwater pooling on the surface.

Current underground stormwater storage systems may expose in situ subgrade soils to moisture when subjected to minor volumes of storage. Soils susceptible to shrink and swell from varying moisture contents may reflect unwanted movement to pavements or structures at the surface. Liners may be used to protect subgrade soils, but may not be properly installed or inspected for complete watertightness. In an effort to prevent the overloading of an underground stormwater storage system and minimize unwanted movement of subgrade soils, improvements to an underground stormwater storage system may be desired.

BRIEF DESCRIPTION OF THE DRAWINGS

These drawings illustrate certain aspects of some of the embodiments of the present invention and should not be used to limit or define the invention.

FIG. 1 illustrates a perspective view of an underground stormwater storage system;

FIG. 2 illustrates a perspective view of a structure and an outlet;

FIG. 3 illustrates a perspective view of an alternative embodiment of a structure and an alternative embodiment of an outlet from FIG. 2;

FIG. 4 illustrates an embodiment of an outlet;

FIG. 5 illustrates an alternative embodiment of an outlet of FIG. 4;

FIG. 6 illustrates an outlet with an attachment point;

FIG. 7 illustrates an embodiment of an aperture with an open one-way valve employing a gasket;

2

FIG. 8A illustrates a perspective view of an alternative embodiment of a stormwater storage system; and

FIG. 8B illustrates a perspective view of an alternative embodiment of a stormwater storage system.

5 FIG. 9 illustrates an alternative embodiment employing treatment chambers 50 and storage chambers 52.

FIG. 10A illustrates an embodiment of a bell siphon employed with a stormwater storage system.

10 FIG. 10B illustrates an alternative embodiment of a bell siphon employed within a stormwater storage structure comprising a bulkhead within a detention structure.

FIG. 10C illustrates an alternative embodiment employing an internal inlet riser for housing a siphon.

15 FIG. 11 illustrates the internal components of a double-bell siphon.

FIG. 12 illustrates an alternative embodiment employing a first solid pipe, a second solid pipe, and a perforated pipe.

FIG. 13 illustrates an alternative embodiment of a bulkhead.

20 FIG. 14 illustrates another alternative embodiment of a bulkhead, which comprises a plurality of orifices.

FIG. 15 illustrates the inside of bulkhead that comprises a filter fabric covering a plurality of orifices.

25 FIG. 16 illustrates an alternative embodiment of the underground stormwater storage system.

FIG. 17 illustrates a perspective view of an additional embodiment of the underground stormwater storage system.

DETAILED DESCRIPTION

30 Embodiments relate generally to an underground stormwater storage system. More particularly, embodiments relate to an underground stormwater storage system which may capture stormwater and expel excess stormwater through outlets. The outlets may be disposed on the uppermost areas of the underground stormwater storage system. In embodiments, an underground stormwater storage system may comprise a structure that may be designed to collect stormwater and release the stormwater underground at a controlled rate of speed. The structure may be buried within an 35 engineered pit under pavement and/or soil. Stormwater may be collected and disposed within the underground stormwater storage system by drain pipes and/or a series of drain pipes. Occasionally, stormwater may be collected in excess 40 due to a flood and/or heavy rain. Large amounts of stormwater may overload underground stormwater storage system, which may prevent stormwater from being removed from the surface. To prevent an overload of the underground stormwater storage system, outlets may be disposed along 45 the top most regions of the underground stormwater storage system. This may allow the water to flow out of the underground stormwater storage system and into an engineered pit in which the underground stormwater storage system is buried. Larger stones, rocks, and dirt may be 50 porous and comprise void areas in which stormwater 55 expelled from the underground stormwater storage system may be disposed, allowing the underground stormwater storage system to continue to function properly.

As illustrated in FIG. 1, an underground stormwater storage system 2 may comprise a structure 4, a pit 6, and a porous backfill 10. In embodiments, the pit 6 may be dug and/or created in any area in which stormwater may need to be collected and disposed of slowly overtime. Areas may include areas where concrete and/or pavement may be used, 60 such as within a city. During rains, concrete and/or pavement may have a tendency to shed and/or collect stormwater. This 65 may prevent stormwater from dissipating into the soil.

Additionally, this may cause stormwater to pool and/or overfill natural stormwater collection areas such as rivers, bayous, and/or lakes. The underground stormwater storage system **2** may be designed to collect, store, and release stormwater within the structure **4**. In embodiments, there may be a plurality of the structures **4** that may be attached to one another to form the underground stormwater storage system **2**. The structure **4** may comprise any suitable cross-sectional shape; a suitable shape may be, but is not limited to a circle, an arch, a square, a rectangle, and/or any combination thereof. Additionally, structure **4** may be of a single radius or a multi-radius shape. In embodiments, the structure **4** may be any suitable material in which to house stormwater underground. Suitable material may be, but is not limited to, plastic, concrete, metal, fiberglass and/or any combination thereof. The structure **4** may further comprise ribbing, not illustrated, which may add additional strength to structure **4**. Once secured underground, the structure **4** may be able to retain and expel stormwater at any engineered rate of speed. When large amounts of stormwater are collected by the underground stormwater storage system **2**, the rate of speed in which stormwater may be expelled from the structure **4** may not be fast enough to allow for the stormwater to move through the underground stormwater storage system **2**, which may cause stormwater to collect and back up within the structure **4**. As stormwater is collected in the structure **4**, the stormwater level in the structure **4** may rise. In embodiments, stormwater may rise to the top of the structure **4**. Outlets **12** may be used to expel water out of the structure **4**, which may allow the underground stormwater storage system **2** to continue the disposal of stormwater from a surface **22**.

FIGS. 2 through 4 illustrate embodiments in which the structure **4** may comprise outlets **12**, which may be disposed on an area of the structure **4** closest to the surface. Outlets **12** may be disposed about the crown and/or top of the structure **4** and may further be disposed in any area above the springline or midrise of the enclosed structure **4** or within the crown and/or haunch of the arch of the structure **4**. The springline may be defined as the line at which an arch begins. Alternatively, in embodiments outlets **12** may be disposed at or below the springline or midrise. Outlets **12** may comprise any suitable shape; a suitable shape may be, but is not limited to, a square, rectangle, oval, circle, polyhedron, and/or any combinations thereof. Additionally, referring to FIG. 2, outlets **12** may be a slot, for example, that traverses the length of the structure **4** and extends up and away from the structure **4** by any suitable length. A suitable length may be as long as about one inch to about twelve inches, about four inches to about ten inches, about six inches to about eight inches, or about six inches to about twelve inches. As illustrated in FIGS. 2 through 4, outlets **12** may be disposed along the crown, a side of the structure **4**, and/or on top of the structure **4**. Without limitation, outlets **12** may be disposed in any area above, at, or below the springline of the structure **4**. Additionally, outlets **12** may be a single outlet or a plurality of outlets **12**. Outlets **12** may be disposed adjacent to one another and may be disposed in random patterns, straight lines, and/or offset from each other. The plurality of outlets **12** may further be disposed above the springline of the structure **4**. Outlets **12** may function to delay the expulsion of stormwater from the structure **4** until large amounts of stormwater are collected within the structure **4**. The structure **4** may collect and/or hold stormwater due to the ability of the structure **4** to retain stormwater.

An enclosed structure, as illustrated in FIGS. 2 and 4, may be sufficiently water tight and may be able to collect

stormwater. In embodiments, referring to FIG. 3, the structure **4** may not be an enclosed structure. A liner **8** may be used to prevent stormwater from dissipating into the porous backfill **10** (not illustrated) continuously. The porous backfill **10** may be, but is not limited to, gravel, limestone, dolomite, stone, shale, and/or any combination thereof. Shaped as an arch, the structure **4** may comprise an open bottom. With an arched structure **4**, the liner **8** may act as a bottom to the structure **4** and sufficiently seal the arch. This may prevent stormwater from dissipating into the pit **6** (not illustrated), which may deposit sand and/or silt within the porous backfill **10**, making the porous backfill **10** impervious to stormwater. The saturation of the porous backfill **10** with sediment may clog the underground stormwater storage system **2**, which may cause stormwater to back up and prevent stormwater from dissipating properly in the underground stormwater storage system **2**. The liner **8** may contain sand and/or silt, preventing it from saturating the porous backfill **10**. The structure **4** may be configured to allow operators to remove sand and/or silt deposited within the structure **4**. By removing deposited sand and/or silt, the structure **4** may be able to increase the amount of stormwater the structure **4** may be able to retain. In instances where large amounts of stormwater are captured, sand and/or silt may settle to the bottom of the structure **4**. This may allow stormwater, void of sand and/or silt, to move upward within the structure **4**. Clean stormwater may then be free to move through outlets **12** and flow into the porous backfill **10**. Clean stormwater may not deposit sand/silt into the porous backfill **10** and may allow an engineer to take into account void areas within the porous backfill **10** in stormwater storage calculations.

In embodiments, outlets **12** may be utilized during storm events in which large amounts of stormwater may be collected by the stormwater storage system **2**. Events in which large amounts of stormwater may be collected may rarely occur. This may further prevent the expulsion of sand and/or silt, disposed within the structure **4**, into the porous backfill **10**. Additionally, preventing the expulsion of water into the porous backfill **10** may further prevent the exposure of subgrade soils to moisture, which may lead to the swelling and shrinkage, erosion and/or removal of subgrade soils. In embodiments, outlets **12** may be designed to allow for the release of stormwater into the porous backfill **10**, but may further prevent the porous backfill **10** from entering the structure **4**.

Outlets **12** may be configured to allow stormwater to be expelled from the structure **4** and prevent the porous backfill **10** from falling into the structure **4**. Outlet **12** may be inserted into the structure **4** before and/or after placement of the structure **4** within the pit **6**. Additionally, outlets **12** may be removable from the structure **4** and may be replaced. As illustrated in FIGS. 5 through 8, outlets **12** may comprise different embodiments and/or shapes to prevent the porous backfill **10** from falling through outlets **12** into the structure **4**. Referring to FIG. 4, outlets **12** may comprise a cover **14**. In embodiments, the cover **14** may have a domed shape, which may allow stormwater to move up and out of outlets **12** under the dome shape, while the top of the dome prevents the porous backfill **10** from falling into outlets **12**. The cover **14** may be made of any suitable material; suitable material may be, but is not limited to, metal, plastic, concrete and/or any combination thereof. The cover **14** may partially cover outlets **12** and/or completely cover outlets **12**. Additionally, the cover **14** may comprise partial hemispherical structures, which may be used to prevent the porous backfill **10** from moving through outlets **12** and may allow stormwater to move through the cover **14**. Referring to FIG. 5, outlets **12**

may comprise a screen 16, which may cover the entirety of outlets 12. The screen 16 may be made of any suitable material; suitable material may be, but is not limited to, metal, plastic, and/or any combination thereof. In embodiments, the screen 16 may be a mesh material, which may comprise a plurality of sections in which stormwater may pass through. The mesh design may prevent large-diameter porous backfill 10 from entering the structure 4, but it may allow stormwater to pass through and be removed from the structure 4. In embodiments, there may be any suitable number of screens 16 disposed on outlets 12. A suitable number of screens 16 may be from about one to about six, about two to about four, or about three to about six. Further, outlets 12 may comprise an attachment point 18 as illustrated in FIG. 6.

FIG. 6 illustrates outlets 12 with the attachment point 18. Attachment point 18 may be any suitable shape; a suitable shape may be a hook, a bar, an arch, and/or any combination thereof. In embodiments, attachment point 18 may be used to connect outlets 12, and thus the structure 4, to a crane and/or other lifting mechanism. Attachment point 18 may allow the structure 4 to be positioned within the pit 6 for use. In embodiments, attachment point 18 may comprise the same material as outlets 12. Additionally, attachment point 18 may be removable from outlets 12 after installation of the structure 4.

FIG. 8 illustrates an embodiment of a round structure 4 with various outlets 12. As previously described, outlets 12 may be a slot and/or hole. As shown, outlets 12 may comprise the screen 16 that allows stormwater to pass through it. Outlets 12 may be disposed as a vertical slot about a top portion of the structure 4. In embodiments, outlets 12 may extend along the length of the structure 4. Alternatively, outlets 12 may be disposed as a hole along the top portion of the structure 4.

Returning to FIG. 1, FIG. 1 illustrates an embodiment with an outlet control structure 20. FIG. 1 also shows the surface 22, one or more inlet pipes 24, a connector pipe 26, and an outlet pipe 28. The surface 22 may be cement, grass, asphalt, concrete pavement, or types of pavement, or any other ground cover. The one or more inlet pipes 24 may connect the surface 22, directly or indirectly, to the structure 4. For example, there may be a grating 40 on the surface 22 that allows stormwater to flow into the structure 4, wherein the one or more inlet pipes 24 may be connected to the structure 4. The one or more inlet pipes 24 may be any size and made from any material required for the particular circumstances. For example, in embodiments the one or more inlet pipes 24 may be made from high-density polyethylene (HDPE), corrugated metal, reinforced concrete, polyvinyl chloride (PVC), polypropylene (PP), fiberglass, or other piping materials. Further, in embodiments, the one or more inlet pipes 24 may have any diameter and may be of about 15 inches to 30 inches, 24 inches to 48 inches, 6 inches to 18 inches, and 42 inches to 96 inches. The connector pipe 26 may connect the outlet control structure 20 to the structure 4. The connector pipe 26 may be any size and made from any material required for the particular circumstances and may be about 12 inches to 48 inches. The outlet pipe 28 may connect the outlet control structure 20 to an area for drainage. The outlet pipe 28 may be any size and made from any material required for the particular circumstances. For example, in embodiments, the outlet pipe 28 may be made of HDPE, metal, concrete, PVC, PP, or fiberglass, and in embodiments, the outlet pipe 28 may have a diameter of about 6 inches to 48 inches.

As illustrated in FIG. 1, in embodiments, the outlet control structure 20 may be a rectangular column. Additionally, the outlet control structure 20 may be a column of any shape such as, but not limited to, squared or circular. The outlet control structure 20 may have a height greater than the height of the structure 4. Further, the outlet control structure 20 may comprise an aperture 30 with a one-way valve or valve 32. In embodiments, the outlet control structure 20 may connect to the connector pipe 26 on a wall 20A of the outlet control structure 20. In embodiments, the outlet control structure 20 may connect to the outlet pipe 28 on a wall 20B of the outlet control structure 20. The aperture 30 may have any shape including, but not limited to a rectangular shape, circular shape, or oval shape. In embodiments, the aperture 30 may be located near the bottom of one of the walls of the outlet control structure 20. For example, the aperture 30 may be located on a wall 20C of the outlet control structure 20. The one-way valve 32 may be of any shape or material. In embodiments, it may have a circular shape and made of steel or it may be oval in shape and made of rubber. In embodiments, the one-way valve 32 may be hingedly attached to the top of the aperture 30 or it may be flanged and screwed, bolted, welded or otherwise adhered over aperture 30. The one-way valve 32 may be attached to the outlet control structure 20 in such a way that gravity may assist with inclining the one-way valve 32 towards a closed position. Alternatively, in embodiments, the one-way valve 32 may be positioned at an angle to increase the effect of gravity. As illustrated in FIG. 7, in embodiments, the one-way valve 32 may comprise a gasket 44 or some other similar material for the purpose of decreasing the ability for water to leak through the one-way valve 32. Alternatively, the gasket 44 may be placed inside around the aperture 30 such that the one-way valve 32 may press against the gasket 44 when in or near the closed position.

As illustrated in FIG. 1, in embodiments the outlet pipe 28 may connect to the outlet control structure 20 near the bottom of the outlet control structure 20 in order to improve water drainage. The outlet pipe 28 may be sized to restrict water flow.

In the event of a rainstorm, the following operation of an embodiment of the stormwater storage system 2 may occur. Rain may fall on the surface 22. The stormwater may flow from the surface 22 to the structure 4 by way of the one or more inlet pipes 24, directly or indirectly. As the stormwater flows to the structure 4, the stormwater begins to fill the structure 4, as well as the connector pipe 26 and the outlet control structure 20. The water in the structure 4, the connector pipe 26, and the outlet control structure 20 may have substantially similar head pressures. At this point in the operation, the one-way valve 32 may be inclined to the closed position due, in part, to gravity. The surrounding porous backfill 10 may be relatively dry.

As the water levels in the structure 4, the connector pipe 26, and the outlet control structure 20 rise, the head pressure within the outlet control structure 20 may increase, which may place increased pressure on the one-way valve 32 to prevent the flow of stormwater into the porous backfill 10.

In the event of a small or medium-sized rainstorm, the storage system 2 may fill partially and discharge the rain water at a given rate. In such instances, the backfill 10 may not be needed or used. In the event of a large storm event, the structure 4 may be completely filled with water and may allow water to escape or discharge out of the outlets 12 into the surrounding porous backfill 10. The water discharging out of the outlets 12 may be potentially cleaner than the water in the structure 4 given that large sediments may be

deposited at the bottom of the structure 4. As the rain continues, the water level in the backfill 10 may continue to rise. The water level in the backfill 10 may rise to less than, equal to, or greater than the height of the structure 4.

When the large storm event begins to subside and water is no longer entering the storage system 2, the water level, and thus the head pressure, within the structure 4 and the outer control structure 20 may begin to decrease. A lower head pressure inside the outer control structure 20 may create a differential head pressure between the head pressure inside the outer control structure 20 and the head pressure outside the outer control structure 20 in the backfill 10. This differential head pressure may move the one-way valve 32 from a closed position to an open position, as illustrated in FIG. 12, allowing water to drain from the backfill 10 into the outer control structure 20. The water may continue to drain from the backfill 10, the structure 4, and the outer control structure 20 until the storage system 2 may be substantially drained of water and relatively dry.

Alternatively, the one-way valve 32 may be employed on a wall of the structure 4. For example, as illustrated in FIG. 1, in one embodiment, there may be two or more structures 4, side by side, in a horizontal position underground. These two structures 4 may be connected by an equalizing pipe 34 (not illustrated). In embodiments, as illustrated in FIG. 1, the structure 4 may be a round pipe. In embodiments, the structure 4 may comprise a reinforced bulkhead 46 at one end of the structure 4. At the top of the reinforced bulkhead 46, the structure 4 may comprise an opening 48, as illustrated in FIG. 1. In embodiments, the opening 48 may comprise a wire mesh. Further, in embodiments, the wire mesh may be 0.5-inch galvanized wire mesh. In the embodiment illustrated in FIG. 1, the reinforced bulkhead 46 further comprises the aperture 30 near the bottom. In embodiments, the aperture 30 may be round. In embodiments, a one-way valve 32 may be hingedly attached to the reinforced bulkhead 46 in such a way as to cover aperture 30 when the one-way valve 32 is in the closed position. In embodiments, the one-way valve 32 may have a diameter of 6 inches. In embodiments, the elevation of the one-way valve 32 may vary. Further, in embodiments, the one-way valve 32 may be covered by a sleeve (not illustrated) extending out from the reinforced bulkhead 46. In embodiments, the outlet pipe 28 may lead to a capped perforated riser 36 (not illustrated) in a sewer system 38 (not illustrated). In embodiments, there may be any number of structures comprising the storage system 2.

As illustrated in FIG. 1, reinforced bulkhead 46 may have an inlet control structure 50 as well as inverted pipe 52, which may address problems with trash in the structure 4. Other alternatives may include a redundant one-way valve 32 at higher elevations, riser filters, floc logs baskets, and trash baffles. Further, the storage system 2 may be used with pre/post treatment devices. In embodiments, structure 4 may have more than one one-way valve 32. In embodiments, the outlet control structure 20 may have more than one one-way valve 32. In embodiments, the structure 4 and the outlet control structure 20 may each have one or more one-way valves 32. As discussed above, in embodiments, outlets 12 may be inverted pipe 52 with the downward inlet located within structure 4 or within outlet control structure 20 whereby trash, debris, oils, hydrocarbons or other floatable pollutants may rise above the downward facing inlet to prevent expulsion into porous backfill 10.

As illustrated in FIG. 15A, in another embodiment, structure 4 may comprise an additional reinforced bulkhead 46 internally. The additional reinforced bulkhead 46 may com-

prise one or more one-way valves 32, and it may also comprise an opening 48. In operation, stormwater flows into a portion of structure 4 referred to as a detention system 54. As the level of stormwater in detention system 54 increases, the stormwater forces the one-way valves 32 open allowing stormwater to flow into a portion of structure 4 referred to as a cistern 56. The opening 48 allows air to escape the cistern 56. Additionally, the opening 48 may also allow stormwater to flow from detention system 54 into cistern 56, which may allow silt and trash to remain in the detention system 54. Stormwater may also exit the detention system 54 by way of outlet pipe 28. The stormwater stored in cistern 56 may be employed for use in irrigation or other applications. Multiple cisterns 56 may be created throughout the system 2 and may be connected to one another with sufficiently watertight pipe or other connections to allow equal filling from rainfall harvesting and draining from irrigation or other use.

Alternatively, as illustrated in FIG. 15B, the stormwater may flow directly into cistern 56. In this embodiment, opening 48 allows stormwater overflow to flow into the detention system 54.

FIG. 9 illustrates an alternative embodiment employing treatment chambers 58 and storage chambers 60. The embodiment of FIG. 9 may function similarly to the embodiment shown in FIG. 1, but the embodiment of FIG. 9 may preferentially discharge to storage chambers 60. Further, the embodiment of FIG. 9 may allow for the drainage of stormwater from storage chambers 60 back into treatment chambers 58 through one-way valves 32. In embodiments, stormwater enters the treatment chambers 58 through inlet pipes 24. In embodiments, a small rain storm and/or first flush runoff may be contained in the treatment chambers 58, and treatment chambers 58 may also capture sediment, trash, and other debris. In embodiments, as the amount of stormwater in treatment chambers 58 increases, the head pressure against the one-way valves 32 may increase, keeping the one-way valves 32 in the closed position. In embodiments, treatment chambers 58 must fill with stormwater to the top before spilling into the storage chambers 60. In embodiments, treatment chambers 58 may be connected to storage chambers 60 by one or more overflow pipes 68. In embodiments, trash and other floatable debris may be prevented from entering storage chamber 60 by employing a down-turned connector pipe 26, a baffle wall, or a screen. Further, storage chambers 60, in embodiments, may also be connected to treatment chambers 58 by return pipes 62. In embodiments, return pipes 62 may fill with stormwater at the same time storage chambers 60 fill with stormwater. In embodiments, one-way valves 32 in the bulkhead of treatment chamber 58 may prevent stormwater from entering treatment chamber 58 when the head pressure inside treatment chamber 58 exceeds the head pressure inside return pipe 62. In other embodiments, a return pipe 62 may be connected to an outlet control structure 20, wherein the outlet control structure 20 may also be connected to treatment chamber 58 by way of a connector pipe 26. In such embodiments, the outlet control structure 20 may fill with stormwater when the treatment chamber 58 fills with stormwater, and the head pressure inside outlet control structure 20 may maintain the one-way valves 32 until the head pressure inside return pipe 62 exceeds the head pressure inside outlet control structure 20. In embodiments, as treatment chambers 58 drain through outlet pipes 28, directly or indirectly, the level of stormwater in treatment chambers 58 decreases, which may ultimately create a differential head pressure needed to open the one-way valves 32. In embodi-

ments, once one-way valves 32 are open, the treatment chambers 58 and storage chambers 60 drain approximately simultaneously and substantially completely. This alternative embodiment may allow for easier maintenance since the trash, debris, and pollutants may be isolated, and it may allow for the use of filters, chemicals, and other finer treatment methods and devices. Further, this alternative embodiment may further protect the backfill 10 given that the backfill 10 may only receive the cleanest discharge from the tops of storage chambers 60 in very large storm events. Additionally, there may be other alternative embodiments in which a perforated pipe (not illustrated) may be set into or buried under backfill 10 for additional drainage. Further, in this alternative embodiment, a pump (not illustrated) may be employed to assist with this additional drainage.

FIGS. 10A-10C illustrate embodiments of bell siphons 64 that may be employed to assist with stormwater drainage. In the embodiment of FIG. 10A, a small volume of an outlet control structure 20 may be dedicated to fill very quickly during a storm event. This small volume may be referred to as the siphon area 66 in embodiments. In embodiments, the siphon area 66 may comprise one or more inlet pipes 24 and grating 40. In embodiments, the siphon area 66 may begin filling up with stormwater before the structure 4. In embodiments, as the amount of stormwater in siphon area 66 increases, the head pressure inside the siphon area 66 increases forcing the one-way valves 32 to remain in the close position. In embodiments, when the stormwater reaches the required elevation to prime the siphon 64, stormwater may begin to discharge from the outlet pipe 28 of siphon 64. In embodiments, any excess water in the siphon area 66 may overflow into the detention structure 4 through an overflow pipe 68. In embodiments, as the stormwater outside of the siphon 64 draws down, the elevation of the stormwater in the siphon area 66 may decrease lower than the elevation in the detention structure 4, creating a differential head pressure, which may open the one-way valves 32. In embodiments, the siphon 64 may drain the entire system 2. FIG. 10B illustrates an alternative embodiment comprising a bulkhead 46 within detention structure 4 with one or more inlet pipes 24 or gratings 40. In the embodiment shown in FIG. 10B, the siphon area 66 may be inside structure 4. Further, any overflow of stormwater may flow over bulkhead 46 similar to the embodiment shown in FIG. 8A. FIG. 10C illustrates another alternative embodiment employing an internal inlet riser 70 for housing siphon 64 (not illustrated). In embodiments, any overflow in the embodiment of FIG. 10C may flow out of inlet riser 70 through openings 72 at the top of inlet riser 70 into structure 4. In embodiments, siphon 64, a hydrobrake, or other flow-control device that may benefit from increased head pressure may be placed within the siphon area 66. In embodiments, the benefit of employing a siphon 64 may be that, once primed, siphons operate at a nearly constant discharge rate versus a simple outlet orifice, which only reaches peak discharge when the system 2 is completely full of water. Further, the required detention volume may be the amount of water flowing into the system 2 less the amount of water flowing out of system 2. Thus, in embodiments, the siphon 64 may drain more water thereby reducing the amount of required storage volume.

FIG. 11 illustrates the internal components of a double-bell siphon 74. In embodiments, the double-bell siphon 74 may comprise a siphon 64, guides 76, floats 78, a cup 82, and a warning indicator 80. In the embodiment of FIG. 11, stormwater may enter the siphon area 66 and enter a first area 84. In embodiments, when the stormwater reaches a

level higher than cup 82, the stormwater may begin to fill cup 82. Further, in embodiments, as stormwater rises inside siphon area 66, floats 78 may cause a floating bell 86 to rise as well. Additionally, stormwater may also begin to fill siphon 64 in embodiments. In embodiments, when the stormwater reaches the required elevation to prime the siphon 64, stormwater may begin to discharge from the outlet pipe 28 of siphon 64. The benefit of this double-bell siphon alternative is that it may prevent sediment and debris from clogging the bottom of siphon 64. In embodiments, warning indicator 80 may be attached to the top of floating bell 86, and warning indicator 80 may exit an aperture in the surface 22. In embodiments, warning indicator 80 may warn property owners, property management, or other individuals that the siphon area 66 may contain excessive debris or have other issues, if the warning indicator 80 fails to return to its subsurface position after the storm has ceased for a reasonable amount of time.

FIG. 12 illustrates an alternative embodiment employing a first solid pipe 100, a second solid pipe 102, and a perforated pipe 104. In embodiments, first solid pipe 100 and second solid pipe 102 may comprise an inner diameter between 24 and 144 inches. Further, in embodiments first solid pipe 100 and second solid pipe 102 may be placed horizontally on liner 8 or porous backfill 10, as illustrated in FIG. 12. Additionally, in embodiments first solid pipe 100 and second solid pipe 102 may be placed horizontally at the same elevation. In embodiments, first solid pipe 100 and second solid pipe 102 may be connected to each other by a connector pipe 106. In embodiments, connector pipe 106 may be attached to the lower half of first solid pipe 100 and also attached to the lower half of second solid pipe 102. In embodiments, connector pipe 106 may be oriented horizontally and level with a slope at or near zero. In embodiments, perforated pipe 104 may comprise an inner diameter between 18 and 136 inches. In embodiments, the inner diameter of perforated pipe 104 may be less than the inner diameters of first solid pipe 100 and second solid pipe 102. In embodiments, perforated pipe 104 may comprise a plurality of perforations 108, which may allow water to flow into and out of perforated pipe 104. In embodiments, perforated pipe 104 may be placed on liner 8 or porous backfill 10 in a horizontal orientation. Further, in embodiments, perforated pipe 104 may be connected to second solid pipe 102 by a flowline pipe 110. In embodiments, perforated pipe 104 may be placed at a higher elevation than first solid pipe 100 and second solid pipe 102. In embodiments, flowline pipe 110 may be attached to the lower half of second solid pipe 102 and also attached to the lower half or upper half of perforated pipe 104. In embodiments, flowline pipe 110 may be positioned with a higher elevation than connector pipe 106. Further, in embodiments, flowline pipe 110 may be positioned at an elevation that does not allow silt-laden water from small storms to flow from second solid pipe 102 into flowline pipe 110. Therefore, in such embodiments, the silt-laden water would remain at the bottom of first solid pipe 100, possibly connector pipe 106, and possibly the bottom of second solid pipe 102.

In embodiments, stormwater may enter first solid pipe 100 through one or more inlet pipes 112. In embodiments, water from a small rain storm and/or first flush runoff may be contained in first solid pipe 100 connected to inlet pipe 112. In embodiments, first solid pipe 100 may also capture sediment, trash, and other debris. In embodiments, water from the small rain storm and/or first flush runoff may flow into connector pipe 106 and second solid pipe 102. In embodiments, as the amount of stormwater increases in first

solid pipe 100, water may begin to flow into connector pipe 106 and second solid pipe 102. In embodiments, as the amount of stormwater increases in second solid pipe 102, stormwater may begin to flow into flowline pipe 110 once the stormwater in second solid pipe 102 reaches the level of flowline pipe 110. In embodiments, this stormwater flowing into flowline pipe 110 may then flow into perforated pipe 104. In embodiments, stormwater flowing in to perforated pipe 104 may eventually reach the elevation of one or more of the plurality of perforations 108, which would allow the stormwater to flow from inside perforated pipe 104 into porous backfill 10. In embodiments, once the storm begins to subside, water from porous backfill 10 may flow back into perforated pipe 104, through flowline pipe 110, and into second solid pipe 102 and first solid pipe 100, through connector pipe 106, and through an outfall 113. Alternatively, some or all of water from porous backfill 10 may percolate into surrounding soil withing pit 6.

FIG. 13 illustrates an alternative embodiment of a bulkhead 120. In embodiments, bulkhead 120 may comprise an opening 122 and a first orifice 124. Thus, in embodiments employing alternative bulkhead 120, stormwater would be permitted to flow through first orifice 124 into porous backfill 10. In embodiments, this flow of stormwater into porous backfill 10 may occur even during small storm events with less volume of water flowing into system 2. In embodiments, first orifice 124 may comprise a diameter between 1 inch and 15 inches. Alternatively, first orifice 124 may be comprised of a trapezoidal shape with parallel sides between 3 inches and 48 inches and non-parallel sides between 1 inch and 30 inches. Alternatively, first orifice 124 may be comprised of an irregular shape with varying dimension between 2 inches and 100 inches. Further, in embodiments, first orifice 124 may comprise a diameter that restricts flow so that the stormwater may fill the pipe employing bulkhead 120 faster than stormwater may flow through first orifice 124 and limit use of backfill 10. In embodiments, the interior of bulkhead 120 may comprise a filter fabric 126, which may cover first orifice 124. In embodiments, filter fabric 126 may prevent silt, trash, sediment, or other materials from flowing through first orifice 124 while still allowing stormwater to flow through first orifice 124. Additionally, in some instances, filter fabric 126 may clog with silt, trash, sediment, or other materials, which may prevent the stormwater from flowing through the first orifice 124 and thus causing the stormwater to initially be stored in the first solid pipe 100 and/or second solid pipe 102, which may result in delayed use of the porous backfill 10. Further, in embodiments as a storm event subsides and stormwater levels in the pipe attached to bulkhead 120 decrease, water may begin to flow from porous backfill 10 through first orifice 124 into the pipe attached to bulkhead 120.

FIG. 13 also illustrates an embodiment comprising a second orifice 128. In embodiments, second orifice 128 may be a plurality of additional orifices. In embodiments, second orifice 128 may comprise a diameter between 1 inch and 15 inches. Alternatively, second orifice 128 may comprise a trapezoidal shape with parallel sides between 3 inches and 48 inches and non-parallel sides between 1 inch and 30 inches. Alternatively, second orifice 128 may be comprised of an irregular shape with varying dimension between 2 inches and 100 inches. In embodiments, second orifice 128 may be positioned above first orifice 124. In embodiments, second orifice 128 may allow for additional water flow out of the pipe attached to bulkhead 120 in larger storm events resulting in higher levels of stormwater in the pipe attached to bulkhead 120.

FIG. 14 illustrates another alternative embodiment of bulkhead 120, which comprises a plurality of orifices 130. FIG. 14 illustrates an embodiment in which the plurality of orifices 130 are laid out in horizontal rows wherein the number of orifices 130 increases as the elevation increases. In embodiments, the first row of orifices 130 may begin with a single orifice 130 and then increase by one additional orifice 130 for each row. In alternative embodiments, each row of orifices 130 may comprise a single orifice 130 or any other design or number of orifices 130. In embodiments, the number and orientation of orifices 130 may allow for control of water flow through bulkhead 120.

FIG. 15 illustrates the inside of bulkhead 120 that comprises filter fabric 126 covering the plurality of orifices 130. In embodiments, filter fabric 126 may be cut in order to cover any design, orientation, and number of orifices 130. Additionally, in embodiments any type of appropriate filter media may be used instead of filter fabric 126. In embodiments, filter fabric 126 as illustrated in FIG. 13 or FIG. 15 may be placed directly against first orifice 124, second orifice 128, and/or the plurality of orifices 130. Alternatively, filter fabric 126 may be placed against a weir (not illustrated), which may allow for some space between the filter fabric 126 and first orifice 124, second orifice 128, and/or the plurality of orifices 130. Additionally, filter fabric 126 employing a weir may aid in slowing the flow of water to porous backfill 10 as well as collect silt. Further, in embodiments a structure employing filter fabric 126 and a weir may be configured so that the top of the weir may allow stormwater to spill over the weir when stormwater levels reach a certain elevation. In embodiments, such a weir structure would act as a safety release of stormwater to porous backfill 10 in the event filter fabric 126 became completely clogged or blocked.

FIG. 16 illustrates an alternative embodiment of the underground stormwater storage system 2. In the alternative embodiment, the underground stormwater storage system 2 comprises at least one solid pipe 150 and a perforated pipe 152. In embodiments, solid pipe 150 may comprise an inner diameter between 24 inches and 180 inches. Further, in embodiments solid pipe 150 may be placed horizontally on liner 8 or porous backfill 10, as illustrated in FIG. 16. Additionally, in embodiments solid pipe 150 may be connected to one or more inlet pipes 112. In embodiments, perforated pipe 152 may comprise an inner diameter between 24 inches and 180 inches. In embodiments, the inner diameter of perforated pipe 152 may be less than or greater than the inner diameter of solid pipe 150. In embodiments, perforated pipe 152 may comprise a plurality of perforations 108, which may allow water to flow into and out of perforated pipe 152. In embodiments, perforated pipe 152 may be placed on liner 8 or porous backfill 10 in a horizontal orientation. Further, in embodiments, perforated pipe 152 may be connected to solid pipe 150 by connector pipe 110. In embodiments, connector pipe 110 may be attached to the lower half of solid pipe 150 and also attached to the lower half of perforated pipe 152. Further, in embodiments, connector pipe 110 may be positioned at an elevation that does not allow silt-laden water from small storms to flow from solid pipe 150 into connector pipe 110. Therefore, in such embodiments, the silt-laden water would remain at the bottom of solid pipe 150. Additionally, in embodiments a cap 154 may be employed at the junction of connector pipe 110 and perforated pipe 152. Further, in embodiments a plurality of solid pipes 150 and/or perforated pipes 152 may be employed.

In embodiments, the alternative embodiment illustrated in FIG. 16 may provide for solid pipe 150 to receive stormwater through inlet pipes 112. However, during the construction phase of a surface project, in which debris may be washed into the inlet pipes 112 and solid pipe 150, the cap 154 may be employed to prevent usage of perforated pipe 152 and porous backfill 10. In embodiments, the cap 154 may be installed at the junction of the connector pipe 110 and perforated pipe 152. Thus, in embodiments, stormwater containing dirt and/or debris may be held in solid pipe 150 until the construction site is stable. In embodiments, once the construction site is stable, the cap 154 may be removed allowing full usage of the volume in the perforated pipe 152 and porous backfill 10. Thereafter, in embodiments, stormwater may enter solid pipe 150 through one or more inlet pipes 112. In embodiments, solid pipe 150 may capture sediment, trash, and other debris.

FIG. 17 illustrates a perspective view of an additional embodiment of the underwater stormwater storage system 2. In embodiments, more than one solid pipe 150 may be placed in line as shown in FIG. 17. In embodiments, the bulkheads 120 of each solid pipe 150 may be removed, and the solid pipes 150 may be connected to each other using a connecting joint 180. In embodiments, the connecting joint 180 may be uncovered or the connecting joint 180 may be covered with a band 182. In embodiments, the band 182 may comprise a standard band that would be known to a person of ordinary skill in the art. In embodiments, the band 182 may comprise a plurality of orifices. In embodiments in which the band 182 comprises a plurality of orifices, stormwater may be discharged from the solid pipes 150 through the gap 184 into the porous backfill 10 at a slower rate than the stormwater collecting in the solid pipes 150. Alternatively, in embodiments the connecting joint 180 may be covered with fabric 126 (not illustrated). In such embodiments, stormwater may be discharged from the solid pipe 150 and through the fabric 126 at a slower rate than the stormwater collecting in the solid pipes 150. In embodiments, the connecting joint 180 may provide a gap 184 of roughly $\frac{1}{2}$ inch between the solid pipes 150, wherein the connecting joint 180 may allow for the free flow of stormwater from the solid pipe 150 into the porous backfill 10. However, in embodiments the stormwater may contain sediment, trash, and other debris. In such embodiments, the sediment, trash, and/or other debris may create a barrier 186 to the free flow of the stormwater into the porous backfill 10. In embodiments, the barrier 186 created by the sediment, trash, and/or other debris may delay the flow of stormwater into the porous backfill 10 until the stormwater in the solid pipe 150 reaches an elevation higher than the barrier 186. In embodiments employing a band 182 over the connecting joint 180, the band 182 may be loosened to allow stormwater to flow from the gap 184 into the porous backfill 10. In such embodiments, the barrier 186 created by any sediment, trash, and/or other debris may likewise cause stormwater to build up within the gap 184 until the stormwater reaches an elevation higher than the barrier 186. Similarly, in embodiments employing fabric 126 over the connecting joint 180, stormwater may freely flow through the fabric 126 into the porous backfill 10. However, in embodiments the barrier 186 may delay the flow of the stormwater into the porous backfill 10 until the stormwater in the solid pipes 150 reaches an elevation higher than the barrier 186. Additionally, in embodiments the more than one solid pipe 150 laid in line may not be connected by the connecting joint 180. In alternative embodiments, the gap 184 between the more than

one solid pipe 150 may be created by simply placing the solid pipes 150 close together without touching. In embodiments, this gap 184 may likewise be covered with band 182 or fabric 126. Thus, in embodiments the connecting joint 180 and/or gap 184 may protect the void space within the porous backfill 10 from contamination.

The foregoing figures and discussion are not intended to include all features of the present techniques to accommodate a buyer or seller, or to describe the system, nor is such figures and discussion limiting but exemplary and in the spirit of the present techniques.

What is claimed is:

1. An underground stormwater storage system, comprising:
an inlet pipe;
a porous backfill, wherein the porous backfill comprises stones;
a first structure, wherein the first structure comprises two bulkheads, wherein one bulkhead is disposed on each end of the first structure, and further wherein the interior of the first structure is capable of receiving and holding stormwater from the inlet pipe;
a second structure, wherein the second structure comprises two bulkheads, wherein one bulkhead is disposed on each end of the second structure, and further wherein the second structure comprises a plurality of perforations;
a connector pipe, wherein the connector pipe is fluidly connected to the first structure and the second structure; and
an outfall, wherein the outfall is fluidly connected to the connector pipe.
2. The underground stormwater storage system of claim 1, wherein the system comprises additional structures, wherein each of the additional structures are fluidly connected to the connector pipe.
3. The underground stormwater storage system of claim 1, wherein the inner diameter of the second structure is less than the inner diameter of the first structure.
4. The underground stormwater storage system of claim 1, wherein the second structure is positioned at a higher elevation than the first structure.
5. The underground stormwater storage system of claim 1, wherein the connector pipe is fluidly connected to one of the bulkheads of the first structure and one of the bulkheads of the second structure.
6. The system of claim 1, wherein the system further comprises a cap positioned at a pipe of the second structure.
7. An underground stormwater storage system, comprising:
an inlet pipe;
a porous backfill, wherein the porous backfill comprises stones;
a first structure, wherein the first structure comprises two bulkheads, wherein one bulkhead is disposed on each end of the first structure, and further wherein the interior of the first structure is capable of receiving and holding stormwater from the inlet pipe;
a second structure, wherein the second structure comprises two bulkheads, wherein one bulkhead is disposed on each end of the second structure, and further wherein one of the bulkheads of the second structure comprises a plurality of orifices;
a connector pipe, wherein the connector pipe is fluidly connected to the first structure and the second structure; and

15

an outfall, wherein the outfall is fluidly connected to the connector pipe.

8. The system of claim 7, wherein one of the bulkheads of the second structure comprises a first orifice below the springline of the bulkhead. 5

9. The system of claim 8, wherein the interior side of the first orifice is covered by a filter fabric.

10. The system of claim 7, wherein a second orifice is positioned at a higher elevation than the first orifice.

11. The system of claim 7, wherein the plurality of orifices 10 are organized in horizontal rows.

12. The system of claim 11, wherein the surface area of orifices increases in each horizontal row as the elevation increases.
